(57) **CLAIM**

The ornamental design for a display screen or portion thereof with graphical user interface, as shown and described.

DESCRIPTION

FIG. 1 is a front view of a display screen or portion thereof with graphical user interface showing our new design; FIG. 2 is a front view of a display screen or portion thereof with graphical user interface showing our new design; and, FIG. 3 is a front view of a display screen or portion thereof with graphical user interface showing our new design.

The broken lines around the Figures showing a display screen or a portion thereof form no part of the claimed design.

The appearance of the animated image on the display screen sequentially transitions between the images shown in FIGS. 1-3.

1 Claim, 1 Drawing Sheet
